UNITED STATES PATENT OFFICE.

CHARLES C. SCHRODER, OF CHICO, CALIFORNIA.

AUTOMATIC MATRIX CLEANER.

Application filed May 26, 1924. Serial No. 715,858.

This invention relates to attachments for typesetting machines and particularly to a device especially designed to be used on standard linotypes; the principal object of my invention being to provide a device which will keep the reading faces of the matrices used in such machines in a continuously clean and legible condition, and without any attention on the part of the operator being necessary other than an occasional adjustment of the cleaning element.

Another object is to provide a device for the purpose which may be attached to the machine in but a few seconds' time, and without making changes of any character to the machine.

A further object is to construct the device in such a manner that while the cleaning element is normally in contact with the reading faces of the matrices, it may be readily moved away from its normal position when it is necessary to remove any matrices from the line, without having to detach the device from the machine and without permanently disturbing its normal setting.

A further object of the invention is to produce a simple and inexpensive device and yet one which will be exceedingly effective for the purpose for which it is designed.

These objects I accomplish by means of such structure and relative arrangement of parts as will fully appear by a perusal of the following specification and claims.

In the drawings similar characters of reference indicate corresponding parts in the several views:

Fig. 1 is a perspective outline of the assembling block structure of a linotype, showing my improved cleaner applied thereto.

Fig. 2 is an enlarged vertical cross section of the attachment in connection with the block and a matrix.

Fig. 3 is a top plan view of the device.

Referring now more particularly to the characters of reference marked on the drawings, the numeral 1 denotes a horizontal bar having a ledge 2, on its inner face a certain distance from the top thereof. Transversely spaced from said bar is a vertical back-plate 3 also having a ledge 4 facing and in vertical alinement with the ledge 2. These members form part of the assembly block structure of a standard linotype, the matrices used in connection with the typesetting operations being fed between the members 1 and 3 with such operation and resting on

the ledges 2 and 4. The means employed in thus feeding the matrices and moving them along is well known to all linotype operators and others versed in the art, and forms no part of my invention.

The matrices are disposed with their reading-face edges facing the bar 1, the reading letters 6 impressed thereon and which correspond to the casting letters on the opposite edge, being disposed on said edges just above the top of the bar 1.

The bar 1, on the outer face thereof, has a horizontal rod or shaft 1 and a concentric boss or hub 8 adjacent one end thereof, and these members which are standard parts, I make use of in mounting my cleaning attachment.

The latter comprises a rigid vertical piece 9 bent at its lower end to form a horizontal part 10 extending under the bar 1.

Provided with the member 9 on opposite sides thereof and projecting inwardly therefrom or towards the bar 1 are saddles 11 and 12 adapted to rest on and partially surround the members 7 and 8 respectively, the saddle 11 having a vertical portion 13 at its inner end adapted to abut against the outer vertical face of the bar 1. An adjustable screw 14 is mounted in the lower part 10 of the attachment and bears against the under face of the bar 1. It will therefore be seen that by means of the above described construction, the members 9 and 10, which constitute the main frame or support of the attachment, may be firmly yet detachably secured to the machine. Hinged onto the upper end of the frame member 9 by means of a horizontal pin 15 parallel to the bar 1 is a vertical piece 16 bent at its upper end to form a horizontal part 17 which extends toward the bar 1 and is adapted to abut against the outer face and adjacent the upper end of said bar. Said part is normally maintained thus abutted by means of a flat spring 18 secured to the member 9 below the hinge and bearing against the member 16 on the outer face thereof.

Fixed on the top of the part 17 is a horizontal casing 19, open at both ends in a plane at right angles to the bar 1. A pad of felt 20, especially treated as hereinafter described, is slidably fitted into the casing from the outer end thereof, and projects beyond the other end to abut against the reading faces of a number of the matrices 5 simultaneously. Since the level of

the reading letters 6 thereon is somewhat lower than the normal level of the felt, which is necessarily a certain distance above the bar 1, a rigid hood or deflector 21 is formed with the casing at the top and forward end thereof, which causes the adjacent end of the felt to be deflected downwardly the necessary distance as plainly shown in Fig. 2.

10 To hold the felt set in the desired position a clamp 22 of suitable character is mounted in connection with the casing.

To raise the member 17, and parts connected thereto at will so that the pad 20 is clear 15 of the matrices, and to enable said raised position to be maintained, I pivot on the inner face of the member 9 a rigid arm 23, formed at its upper end with a wedge shaped portion 24 whose apex faces the upper member 16, and said portion flaring outwardly of the plane of said member 16, as plainly 20 shown in Fig. 3. Upon moving the arm 23 so that the portion 24 approaches the member 16, the latter will be engaged by the 25 wedge, and since the latter is rigid, the said member 16 will be moved outwardly, turning on the pin 15 as an axis, and will remain in such position until the arm 23 is retracted by the operator. This operation 30 withdraws the felt pad from contact with the matrices, and allows any of the same to be readily withdrawn from the line when necessary.

The spring constantly acts to force the 35 member 16 toward the bar, but the part 17 abutting against the bar, the movement of said member 16 is limited, so that the pad cannot be pressed into binding engagement with the matrices.

40 The felt, previous to its insertion into the casing, is boiled for ten minutes or so in a solution consisting of one part wood ash, 3 parts common salt and 12 parts vinegar. The felt is then dried in a vise, to drain excess solution therefrom and to insure that it will be perfectly flat when dry.

The felt is thus hardened and then has considerable rigidity, and offers great resistance to wear.

50 The ingredients of the solution, with which the felt is saturated, act on the matrix to keep the surface thereof contacted by the felt, in a clean and polished state, and free of dirt, so that the impressed letters thereon are thoroughly legible at all times.

From the foregoing description it will be readily seen that I have produced such a device as substantially fulfills the objects of the invention as set forth herein.

60 While this specification sets forth in detail the present and preferred construction of the device, still in practice such deviations from such detail may be resorted to as do not form a departure from the spirit of the invention, as defined by the appended claims.

Having thus described my invention what I claim as new and useful and desire to secure by Letters Patent is:

1. A matrix cleaner comprising a felt pad, impregnated with wood ash, sodium chloride and vinegar.

2. A cleaning device for the reading faces of linotype matrices when positioned in the assembling block of a linotype, comprising a cleaning pad disposed to contact with said faces, a structure supporting the pad, and clamping means on said structure for frictionally and detachably engaging the surface of block.

3. A cleaner for the reading faces of linotype matrices when positioned in the assembling block of a linotype, comprising a cleaning pad disposed to contact with said faces, means for supporting said pad on the block, and means for enabling the pad to be moved entirely clear of the matrices without detaching the supporting means from the block, whereby to enable a matrix to be removed from the block without interference with the pad.

4. A cleaner for the reading faces of linotype matrices when positioned in the assembling block of a linotype, said block including a horizontal bar in front of the matrices and a horizontal rod in front of and parallel to the bar; comprising a frame structure detachably hung on the rod, clamping means on the structure to engage the bar for maintaining the former in a fixed position relative to the latter, and a cleaning pad supported from the frame structure and adapted to engage the reading faces of the matrices.

5. A cleaner for the reading faces of linotype matrices when positioned in the assembling block of a linotype, said block including a horizontal bar in front of the matrices and a horizontal rod in front of and parallel to the bar; comprising a frame structure projecting downwardly outside the rod and having a horizontal portion extending under the bar, a saddle on the frame seating on the rod, an adjustment screw in the horizontal frame portion bearing against the under face of the bar, and a cleaning pad supported from the frame structure and overhanging the bar to engage the matrices.

6. A cleaner for the reading faces of linotype matrices when positioned in the assembling block of a linotype, comprising a cleaning pad disposed to contact with said faces, means for supporting the pad on the block, means for adjusting the pad relative to the faces, and independent means for moving the pad clear of the matrices without disturbing the adjustment and without dismounting the pad from the block.

7. A cleaner for the reading faces of linotype matrices when positioned in the assembling block of a linotype, said block in-

cluding a horizontal bar in front of the matrices, a frame structure mounted in connection with said bar, a cleaning pad mounted with said frame structure and overhanging the bar to engage the matrices, and means mounted on said frame structure for enabling the pad to be withdrawn entirely clear of the matrices without detaching the frame.

10. 8. A cleaner for the reading faces of linotype matrices when positioned in the assembling block of a linotype, said block including a horizontal bar in front of the matrices, a frame structure mounted in connection with said bar, a cleaning pad on top of the bar and engaging the matrices, and a supporting means for said pad hinged to the structure in an axis parallel to the bar.

9. A cleaner for the reading faces of linotype matrices when positioned in the assembling block of a linotype, said block including a horizontal bar in front of the matrices, a frame structure mounted in connection with said bar a cleaning pad on top of the bar and engaging the matrices, a supporting means for said pad hinged to the structure in an axis parallel to the bar, a cam member mounted on the frame structure and engageable with the supporting means to turn the same away from the bar, and spring means resisting such turning movement.

10. A cleaner for the reading faces of linotype matrices when positioned in the assembling block of a linotype, said block including a horizontal bar in front of the matrices, a frame structure mounted in connection with said bar, a cleaning pad on top of the bar and engaging the matrices, a supporting means for said pad hinged to the structure in an axis parallel to the bar, a cam member mounted on the frame structure and engageable with the supporting means to turn the same away from the bar, spring means acting to move the supporting means towards the bar, and means limiting such movement of the supporting means.

11. A cleaner for the reading faces of linotype matrices when positioned in the assembling block of a linotype, said block including a horizontal bar in front of the matrices, a frame structure mounted in connection with said bar, a cleaning pad on top of the bar and engaging the matrices, a supporting means for said pad hinged to the struc-

ture in an axis parallel to the bar, a cam member mounted on the frame structure and engageable with the supporting means to turn the same away from the bar, and spring means resisting such turning movement, the inner end of said supporting means being adapted to normally abut against the bar, whereby to prevent the spring from pressing the pad too firmly against the matrices.

12. A cleaner for the reading faces of linotype matrices when positioned in the assembling block of a linotype, comprising a rectangular casing open at its front and rear ends, means for supporting said casing on the block, a pad slidably mounted for adjustment lengthwise in the casing and adapted to project beyond one end thereof for contact with the matrix faces, and clamping means mounted on the casing and projecting inwardly thereof to engage the pad and hold it in any position to which it may be adjusted.

13. A cleaner for the reading faces of linotype matrices when positioned in the assembling block of a linotype, comprising a rectangular casing open at its front and rear ends, means for supporting said casing on the block, a pad slidably mounted for adjustment lengthwise in the casing and adapted to project beyond one end thereof for contact with the matrix faces, and a downwardly projecting deflector plate provided with the casing at the end thereof adjacent the matrices to deflect the corresponding end of the pad downwardly to the plane of the reading letters of the matrices.

14. A cleaner for the reading faces of linotype matrices when positioned in the assembling block of a linotype, comprising a rectangular casing open at its front and rear ends, means for supporting said casing on the block, a pad slidably mounted for adjustment lengthwise in the casing and adapted to project beyond one end thereof for contact with the matrix faces, and a cleaning pad adapted to engage said faces and having a thickness sufficient only to extend over the reading letters of the faces, whereby the pad as it wears from contact with the edges of the letters may be moved forward to take up such wear as it occurs.

In testimony whereof I affix my signature.
CHARLES C. SCHRODER.
